Primary Examiner — Cynthia Ramirez(74) *Attorney, Agent, or Firm* — Sterne, Kessler,
Goldstein & Fox P.L.L.C.(57) **CLAIM**

The ornamental design for a gimbal, as shown and described.

DESCRIPTION

FIG. 1 is a top front perspective view of a gimbal showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof showing the gimbal in an environment in which it may be used.

The broken lines in the figures show portions of the gimbal that form no part of the claimed design.

1 Claim, 8 Drawing Sheets(56)
